UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

THRESHOLD.

Application filed July 23, 1923. Serial No. 653,231.

To all whom it may concern:

Be it known that I, HERMAN C. MAISE, a citizen of the United States of America, residing at Detroit, in the county of Wayne and State of Michigan, have invented certain new and useful Improvements in Thresholds, of which the following is a specification, reference being had therein to the accompanying drawings.

10 This invention relates to vehicle bodies and refers more particularly to thresholds for door openings therein.

An object of the invention is to provide a single member that forms thresholds for 15 a plurality of door openings in the body.

Another object is to provide a strong and durable member that also serves as a combination weather strip for the doors and an outer panel or finish strip for the body.

20 Another object is to provide a threshold member that is simple in construction and that can be manufactured at a comparatively low cost.

With the above and other objects in view 25 the invention consists in certain novel features of construction, combinations and arrangements of parts as will be more fully described and particularly pointed out in the appended claims.

30 In the accompanying drawing:—

Figure 1 is a side elevation of a motor vehicle embodying my invention;

Figure 2 is a sectional view taken on line 2—2 of Figure 1;

35 Figure 3 is a fragmentary perspective view of the channel member;

Figure 4 is a fragmentary sectional view corresponding to Figure 2 but showing a slightly modified form of construction;

40 Figure 5 is a sectional view taken on line 5—5 of Figure 4;

Figure 6 is a fragmentary sectional view similar to Figure 4 but showing a slightly modified construction.

45 In the manufacture of vehicle bodies, it is usual to provide wooden thresholds for the door openings and to provide metal panels or finish strips for the outer surfaces of the thresholds. However, with such con-

struction it is necessary to attach the thresholds to the usual sills of the body and then to attach the separate panels in position. This requires considerable time, labor and material which is objectionable.

With the present invention the usual 55 wooden threshold and separate outer panel are dispensed with and I preferably provide a single member that performs both functions.

Referring now to the drawing in which 60 like characters of reference designate corresponding parts throughout the several views, the numeral 1 designates a vehicle body of the closed type having door openings 2 and 3 that are preferably arranged 65 adjacent to each other in the side panels of the body and that preferably extend upwardly from a sill 4 of the usual body frame to the top 5. The doors 6 and 7 respectively for the openings may be any 70 suitable construction or design and are pivotally mounted upon suitable posts or standards 8 and 9 respectively extending between the sill 4 and the top 5.

The thresholds 10 for the door openings 75 are preferably formed from one piece of metal that preferably extends between the posts 8 and 9 and that is preferably substantially channel-shaped in form, the said 80 channel preferably having inner and outer walls 11 and 12 respectively and a top 13. The outer wall 12 preferably engages the outer edge of the sill 4 and is preferably provided with an inwardly extending flange 85

14 that is secured to the lower face of the sill, while the inner wall 11 is preferably parallel to the outer wall and is preferably provided with an inwardly extending flange 15 that is secured to the upper face of the sill. The upwardly projecting portion 16 of the outer wall 10 serves as an abutment for the depending return-bent flanges 17 of the doors, while the rear wall 11 preferably extends slightly above the forwardly 90 and downwardly inclined top 13 and is preferably return-bent as shown at 18 to provide an abutment flange for engagement with the inner faces of the doors. Thus,

the thresholds serve as effective weather strips for the doors. The channel-shaped member 10 is preferably enameled so that the outer wall 12 serves as an outer panel or finish strip for the body.

In the modification illustrated in Figures 4 and 5, I have shown a construction in which the member 20 is preferably similar in form to the member 10 and is preferably provided, at spaced points throughout its length, with transversely extending depressed portions 21 that serve as stiffening or reinforcing means for the thresholds. To reinforce the thresholds further, I preferably provide a finish plate 22 that has an outwardly extending portion 23 engaging the top 24 of the member 20, and a downwardly extending portion 25 that engages the rear wall 26 of the member 20. The outwardly extending portion 23 is preferably provided with substantially L-shaped tongues 27 that extend through openings 28 in the top 24 of the member 20 while the flange 29 extends inwardly from the downwardly extending portion 25 of the finish plate and rests upon the inwardly extending flange 30 of the inner wall 26 of the member 20. Suitable screws 31 preferably secure both the flanges 29 and 30 to the sill 32. The portion 25 of the plate 22 preferably projects above the portion 23 and is preferably return-bent as shown at 33 to provide an abutment similar to the abutment 18 for the inner faces of the doors.

In the modification illustrated in Figure 6, I have shown a construction in which the threshold member 40 is preferably provided with parallel outer and inner walls 41 and 42 respectively and is preferably provided with an outwardly and downwardly inclined top 43 that preferably terminates short of the outer wall 41 and that is preferably return-bent as shown at 44. A finish plate 45, preferably similar in form to the plate 22, is used to cover the rear wall 42 and top 43 of the threshold member 40 and is preferably provided with an inwardly extending flange 46 that is secured to the sill 47 in a manner similar to the flange 29. The portion 48 of the finish plate 45 is preferably return-bent similar to the portion 25 of the plate 22, but the outer edge of the portion 49 is preferably bent around the return-bent portion 44 of the threshold top 43 as shown at 50 and serves as an abutment for the depending flanges 51 of the doors 52. Thus, in this construction the outer faces of the doors are flush with the outer wall 41 of the threshold member 40.

While it is believed that from the foregoing description, the nature and advantages of the invention will be readily apparent, I desire to have it understood that I do not limit myself to what is herein shown and described and that such changes may be re-

sorted to when desired as fall within the scope of what is claimed.

What I claim as my invention is:

1. The combination with a vehicle body having a sill and a door opening above the sill, of a separate member secured to said sill and forming a threshold for said opening, and a member extending longitudinally of and detachably secured to certain portions of the member aforesaid and reinforcing the same. 70

2. The combination with a vehicle body having a sill and a door opening above the sill, of a separate inverted channel-shaped member secured to said sill and forming a threshold for said opening, said member having depressed reinforcing portions, and a finish plate engaging the top and back of said channel-shaped member and concealing said depressed portions. 80

3. The combination with a vehicle body having a sill and a door opening above the sill, of a separate inverted channel-shaped member having portions secured to different sides of said body sill and forming a threshold for said opening, and means extending longitudinally of said threshold member for reinforcing said channel-shaped member. 90

4. The combination with a vehicle body having a sill and a door opening above the sill, of a separate threshold member having portions secured to different sides of the sill, and reinforcing means for said threshold member having interlocking engagement therewith. 95

5. The combination with a vehicle body having a sill and a door opening above the sill, of a separate inverted channel-shaped threshold member extending longitudinally of said sill and having substantially parallel flanges secured to opposite sides of said sill, and a member extending longitudinally of the threshold member and forming a stop for a door. 105

6. The combination with a vehicle body having a sill and side panels provided with spaced door openings above the sill, of a separate threshold member extending across said spaced openings and secured to said sill. 110

7. The combination with a vehicle body, having a sill, a side panel secured thereto, having a door opening therein adjacent to the sill, a separate threshold member secured to the sill and extending across the door opening in the panel, said member having a wall concealing the outer edges of the sill. 115

8. The combination with a vehicle body having a sill, a side panel secured thereto having a door opening therein adjacent to the sill, a separate inverted channel-shaped threshold member extending across the door opening in the panel, said member having portions secured to the upper and lower faces of the sill, and a reinforcing member 120

130

secured to the member aforesaid having a shoulder forming a stop for the door.

9. The combination with a vehicle body, having a sill, a side panel secured thereto having a door opening therein, a separate inverted channel-shaped threshold member extending across the door opening in the panel

and secured to the sill, and a reinforcing member extending longitudinally of the member aforesaid secured to the sill and ¹⁰ having a shoulder forming a stop for the door.

In testimony whereof I affix my signature.
HERMAN C. MAISE.
